UNITED STATES PATENT OFFICE.

FERDINAND W. BEARD, OF YOUNTVILLE, CALIFORNIA.

SHOE.

1,127,850.

Specification of Letters Patent.

Patented Feb. 9, 1915.

Application filed April 4, 1914. Serial No. 829,665.

To all whom it may concern:

Be it known that I, FERDINAND W. BEARD, a citizen of the United States, residing at Yountville, in the county of Napa and State 5 of California, have invented certain new and useful Improvements in Shoes, of which the following is a specification:

This invention relates to improvements in shoes, and as its principal object contemplated a leather shoe having a metal sole so formed and shaped as to inclose the toe and heel portion of the foot.

As a further object, the invention aims to provide a metal sole, the longitudinal edges 15 of which, throughout a portion of their length, are so slit and corrugated as to receive the shoe upper or leather portion of the shoe to in this manner effectively fasten the said two parts without the use of thread 20 or nails.

The above and additional objects are accomplished by such means as are illustrated in their preferred embodiment in the accompanying drawings, described in the following 25 specification and then more particularly pointed out in the claims which are appended hereto and form a part of this application.

In describing my invention in detail reference will be had to the accompanying 30 drawings wherein like characters denote like or corresponding parts throughout the several views, and in which:—

Figure 1 is a side elevation, partly broken 35 away, of a shoe manufactured or constructed in accordance with the present invention; Fig. 2 is a section on the line 2—2 of Fig. 1; Fig. 3 is a section on the line 3—3 of Fig. 1; Fig. 4 is a section on the line 4—4 of Fig. 1; 40 and Fig. 5 is an enlarged fragmentary sectional view illustrating in detail the manner in which the shoe upper and sole are connected. Fig. 6 is a similar view, the mode of attachment being slightly modified; Fig. 45 7 is a like view of a still further modification; and Fig. 8 is still another modification.

Referring now to the drawings by numerals, 1 designates, as an entirety, the shoe upper, the same being of leather or other 50 suitable material. The shoe sole, designated as an entirety by the numeral 2, is of metal, preferably steel, and is shaped to form a toe protecting portion 3, a heel protecting portion 4, and a connecting portion 5, the latter 55 extending beneath the arch of the foot.

To resemble, as closely as possible, the

shoe formation as at present preferred, the connecting portion 5 of the sole is provided with upturned flanges 6 upon its respective longitudinal edges, said flanges, as illustrated to advantage in Fig. 5, being designed and shaped to represent the extended portion of the sole common to the ordinary all leather shoes. Said flange 6 is bent upon itself or again into engagement with the sole 60 5 as indicated at 7, and from the latter point slit longitudinally as indicated at 8, the respective extensions formed by the slit 8 being longitudinally corrugated to provide for the retention of the shoe upper 1, the latter 70 fitting between the said extensions, in which position it is fastened by the corrugations or serrations aforesaid. The novel manner in which the said upper is attached to the sole renders the use of thread or nails in the 75 manufacture of the shoe unnecessary and, to a certain extent, prevents water from seeping into the shoe interior.

In the manufacture of rough or work shoes, the extension or flange 6 of the sole 80 may be eliminated and the sole bent upwardly and slit in the manner aforesaid, as the said extension or flange is only provided to add materially to the appearance of the shoe.

Referring now to the modifications illustrated in Figs. 6 to 8 inclusive, the numeral 9 designates a rivet, any number of which may be arranged to more tightly fasten the shoe upper in the slit provided therefor. 90 In Fig. 7, the corrugations have been eliminated and rivets 10 utilized to fasten the upper to the sole between the extensions formed by the slit in the sole edge, while in Fig. 8 the rivets 11 shown therein are the 95 same as in Fig. 7, the sole however being extended as indicated at 12 to add materially to the appearance of the finished shoe.

From the above, taken in connection with the accompanying drawings, it is evident, 100 that by providing a suitable shoe lining, the corrugations at the respective sides of the shoe will in no way chafe or rub the foot of the wearer; that the longevity of the shoe is increased many fold; and that by the 105 toe and heel plate, that portion of the shoe upper most subjected to wear is protected, and the toes and heels of the wearer to a certain extent insured against injury.

In reduction to practice, I have found that 110 the form of my invention, illustrated in the drawings and referred to in the above de-

scription, as the preferred embodiment is the most efficient and practical; yet realizing that the conditions concurrent with the adoption of my device will necessarily vary, 5 I desire to emphasize the fact that various minor changes in details of construction, proportion and arrangement of parts may be resorted to, when required, without sacrificing any of the advantages of my invention, 10 as defined in the appended claims.

Having thus fully described my invention, what I claim as new and desire to secure by Letters Patent, is:—

1. In a shoe, a shoe upper, a sole having 15 its longitudinal edges turned upwardly and slit to receive the upper, and means fastening the said upper to the upturned portion of the sole.

2. In a shoe, a shoe upper, and a metallic 20 sole, the longitudinal edges of which are slit, the extensions formed by the said slit being corrugated, said upper fitting between said extensions and being fastened by the corrugations aforesaid, as and for the purpose set 25 forth.

3. In a shoe, a shoe upper, a metallic sole, the longitudinal edges of the said sole being slit throughout their entire length, the extensions formed by the said slit being corrugated longitudinally throughout their entire length, the said upper fitting between the said extensions, the said corrugations serving as a fastening means therefor, a toe protecting element formed at one end of the said sole, and a heel protecting element 30 formed at the opposite end of the sole, as and for the purpose set forth.

4. A one piece metallic sole for shoes including a toe protecting element, a heel protecting element, and an intermediate portion, the longitudinal edges of the said intermediate portion being slit to receive the shoe upper, as and for the purpose set forth. 40

In testimony whereof I affix my signature in presence of two witnesses.

FERDINAND W. BEARD.
